US0D1063429S

(12) **United States Design Patent** (10) Patent No.: **US D1,063,429 S**
(45) Date of Patent: ** Feb. 25, 2025

(54) **FOLDABLE CHAIR FRAME**

(71) Applicant: **JKL CORPORATION**, Seoul (KR)

(72) Inventor: **Jeh Kun Lah**, Seoul (KR)

(73) Assignee: **JKL Corporation**, Seoul (KR)

(**) Term: **15 Years**

(21) Appl. No.: **35/518,642**

(22) Filed: **Sep. 21, 2023**

(80) **Hague Agreement Data**

Int. Filing Date: **Sep. 21, 2023**

Int. Reg. No.: **DM/231968**

Int. Reg. Date: **Sep. 21, 2023**

Int. Reg. Pub. Date: **Oct. 13, 2023**

(30) **Foreign Application Priority Data**

Mar. 23, 2023 (KR) 30-2023-0010966

(51) **LOC (15) Cl.** **06-01**

(52) **U.S. Cl.**

USPC **D6/368**

(58) **Field of Classification Search**

USPC D6/360, 361, 362, 364, 366, 379, 716,
D6/373, 708.16, 368, 334, 375, 348, 372,
D6/708, 371, 709.2

Assistant Examiner — Hillary Catherine Shepard

(74) Attorney, Agent, or Firm — REISING ETHINGTON,
P.C.

(57) **CLAIM**

The ornamental design for a foldable chair frame as shown and described.

DESCRIPTION

1. Foldable chair frame

1.1:Perspective

1.2:Front

1.3:Back

1.4:Left

1.5:Right

1.6:Top

1.7:Bottom

1 Claim, 7 Drawing Sheets
